CLAIM

The ornamental design of a weaving tool, as shown and described.

DESCRIPTION

FIG. 1 is a front elevational view of a weaving tool, showing my new design;

FIG. 2 is a top plan view thereof;

FIG. 3 is a fragmentary front elevational view of the tip portion thereof;

FIG. 4 is a fragmentary side elevational view of the tip portion thereof;

FIG. 5 is a front elevational view of a second embodiment of that shown in FIG. 1;

FIG. 6 is a top plan view of that shown in FIG. 5;

FIG. 7 is a fragmentary front elevational view of the tip portion of that shown in FIG. 5;

FIG. 8 is a fragmentary side elevational view of the tip portion of that shown in FIG. 5;

FIG. 9 is a front elevational view of a third embodiment of that shown in FIG. 1;

FIG. 10 is a top plan view of that shown in FIG. 9;

FIG. 11 is a fragmentary front elevational view of the tip portion of that shown in FIG. 9; and,

FIG. 12 is a fragmentary side elevational view of the tip portion of that shown in FIG. 9.
